GRINDING WHEEL DRESSING APPARATUS

Nils Hoglund, Summit, N.J.

Application May 25, 1956, Serial No. 587,357

15 Claims. (Cl. 125—11)

My invention relates to contour-forming apparatus, more particularly to improvements in contour grinding wheel dressers.

In certain types of grinders for dressing ball race grooves and seal grooves on ball bearings and some other applications of this type it is necessary to provide complex contours on the grinding wheel where one or more radii are needed to an accuracy of 20 millionth of an inch or better.

It is the principal object of my invention to provide an improved contour forming apparatus or wheel dresser capable of forming complex contours where one or more radii are needed and with an accuracy of millionths of an inch.

It is another object of my invention to provide such a contour-forming apparatus or wheel dresser in which the dressing tool can be made to move parallel of the axis of the wheel being dressed as well as radially and also in which the tool may be made to move through an arc either while the tool support or dressing housing is stationary or moving.

Briefly, in accordance with my invention, I provide a support adapted to be fixed to the grinding wheel apparatus and having mounted on it a slide guide. A dresser slide mounted on this slide guide in turn supports a bracket extending normally thereof and having thereon a slide guide for slidably supporting a housing on which the diamond or dresser tool is mounted and which carries the various slides, cams, followers, prime movers, and controls. The housing is in effect a three compartment housing in one of which is slidably mounted a slide carrying the contour and feed cams for controlling movement of the housing and the tool slide. The feed cam controls movement of the housing in a direction parallel to the axis of the wheel being dressed. The contour feed cam determines the movement of the dressing tool in a radial direction. This contour and feed cam slide also carries a plurality of trippers which operate control switches within the housing in a predetermined order as the slide moves within the housing. These switches control certain circuits which, in turn, control the solenoid operated valves of a fluid operated piston connected to and moving said slide.

In another portion of the housing I mount a tool slide which carries at its outer end a yoke within which is mounted the pivoted tool support.

Mounted on the tool support is another housing containing a bell crank connected to the rotatable tool support and has movement between two positions for rotating said tool support. Switch members within the housing are operated at these positions and control the rotation of the tool support as well as movement of the housing parallel to the axis of the wheel being dressed by controlling the solenoids of the various valves which, in turn, control the fluid to the two fluid operated pistons.

With the ratio and cam slide in one position and the housing at one of its terminal positions, a starting button initiates movement of the slide carrying the feed cam and

contour cam to cause movement of the housing parallel to the axis of the wheel being dressed. The tool slide during this operation moves radially or remains fixed with respect to the housing to form the contour on the dressing wheel until an intermediate portion of the wheel is reached. At this point, the controls stop movement of the housing and initiate movement of the rotatable tool through an arc. The housing is then caused to continue movement to its terminal position. At this position the controls stop all movement of the housing and tool. The reverse action can be brought about by again operating the starting button.

Other objects of the invention will appear in the following description with reference to the drawings, in which:

Fig. 1 shows a front perspective view of apparatus made according to my invention with the housing covers removed to show details of construction;

Fig. 2 is a perspective taken from the rear of Fig. 1;

Fig. 3 is a plan view of apparatus made according to my invention with parts broken away to show details of construction;

Fig. 4 is a side elevation of Fig. 3 with parts broken away to show details of construction;

Fig. 5 is a section taken along the line 5—5 of Fig. 3;

Fig. 6 is a section taken along the lines 6—6 of Fig. 3;

Fig. 7 is a circuit diagram showing the switches and controls for the fluid pressure operated pistons controlling the movement of the housing slides and tool supports; and

Fig. 8 shows the contour of the wheel being dressed.

General description

Referring now to Figs. 1, 2, 3 and 4, apparatus made according to my invention includes mounting plate base 35 supporting a dresser slide 11 for permitting adjustment of the housing designated generally at 12 radially relative to the surface of the wheel being dressed. This housing is slidably supported on a slide guide to be described and mounted on the bracket 11' extending normally to the dresser slide. The housing moves parallel to the axis of the wheel being dressed. The housing is, in effect, a three-compartment housing comprising the portion 13 in which the contour and feed cam slide are mounted, the portion 14 in which the diamond tool slide is mounted and the portion 15 in which the intermediate slide is mounted. The contour and feed cam slide is connected to the fluid pressure operated piston 43'.

Mounted on the outer end of the tool slide 55 is the tool support or yoke 17, rotatably supporting the tool support 17' carrying the dressing tool 19. Mounted on the yoke 17 is the auxiliary housing 20 in which is mounted the mechanism for rotating the tool support and the controls therefore.

Briefly, as the housing moves along the supporting bracket 11' and parallel to the axis of the grinding wheel, the tool slide remains stationary or is fed radially toward and from the wheel being dressed so that the tool may cut the proper contour. As described above, the housing may be stopped intermediate its terminal position and the tool rotated thru an arc to form the true radius or radii shown in Fig. 8.

Housing and support

Referring now to Figs. 3, 4, 5 and 6, the apparatus made according to my invention includes the mounting plate 10 having the slide guide 10'. The dresser or housing slide 11 is slidably supported on slide guide 10' by ball bearing assemblies 25 and 26. The position of the slide 11 can be adjusted by means of a lead screw, not shown, in order to adjust the position of the housing radially of the wheel being dressed.

Slide 11 is provided with a supporting bracket 11' ex-

tending normally thereof and which, in turn, supports the slide guide 27. The housing 12 is slidably supported on slide 27 by means of the ball bearing assemblies 28 and 29, the entire housing being biased to the right (Fig. 5) or away from the viewer (Figs. 3, 4 and 6) by means of biasing spring 30 which is mounted on the bracket 11' and connected to the housing 12 at 31.

Mounted on the bracket 11' is a fixed follower pin 35 carried in a slidable block 36. The position of the block and pin and hence the position of the housing relative to the wheel being dressed is controlled by means of the adjusting screw 21 freely rotatable in the bracket and connected by screw thread to the block 36. As the screw is rotated, the pin moves toward the right or left (Fig. 5) permitting movement of the housing toward the right or left. This determines the position of the housing 12 along the axis of the wheel being dressed.

Feed and contour cam slide

Referring to Figs. 1, 2, 3 and 5, the portion 13 of the housing 12 has received within it the slide which supports the feed cam controlling movement of the housing and the contour cam controlling movement of the dressing tool radially of the wheel being dressed.

The feed and contour cam slide 40 is mounted on ball bearing assemblies 41 and 42. It is connected to the piston rod 43 of the prime mover hydraulic cylinder 43' which includes a fluid pressure operated piston. The piston rod 43 is connected to the slide by means of the coupling collar or split piston block 44.

The piston 43 is fixed to the housing and is fed with fluid under pressure by conduits 45 and 46 controls for which will be described below. The slide 40 can be made to move back and forth within the housing as desired, carrying with it the feed and contour cams.

On the underside of the slide 40 is mounted the feed or ratio cam 50 which has the shape shown. It is urged against the follower pin 35 by means of the spring 30. As the slide moves from left to right (Fig. 3), since the feed cam becomes narrower toward the right, the housing is moved away from the viewer (Fig. 3) and toward the right (Fig. 5). When the slide and feed cam move in the opposite direction, the housing movement of course is reversed. This controls movement of the housing across the wheel being dressed. During this movement of the housing the tool is also caused to be moved radially of the wheel being dressed and also in an arc at a pre-determined point in the travel of the housing across the surface of the wheel being dressed. This will be described later.

The contour cam 51 which controls the radial movement of the dressing tool 19 is mounted on the upper side of the slide 40. The means by which it controls movement of the tool slide will be described below.

Tool slide

Reference is now made to Figs. 1 to 5, inclusive. Mounted within the portion 14 of the housing 12 is the rectangular plate-like slide 55 slidably supported on the ball bearing assemblies 56 and 57. This slide is urged to the right (Fig. 3) and toward the viewer (Fig. 5) by biasing spring 52 mounted in the housing portion 14 and secured to slide 55 (Figure 4) at 53. Supported on the outer end of the slide 55 is the yoke 17. The rotatable tool support 17' supporting the tool 19 is mounted in the yoke. A flexible dust cover 17'' is connected between the yoke 17 and the housing part 14. This permits movement of the slide 55 into and out of the housing but protects the part of equipment mounted within the housing. The tool support 17 is rotatably mounted in the bearings 59 and 60 supported by the yoke 17.

The intermediate or cam follower slide 75 mounted in the portion 15 of the housing is slidably supported in ball bearing assemblies 76 and 77 and is biased to the left (Fig. 5) and toward the viewer (Fig. 3) by means of

biasing spring 78 secured to the slide 75 at 79 and mounted in the housing portion 15.

This slide 75 carries a contour cam follower 80 maintained in contact with the contour cam 51 by the spring 78. The other end of the slide 75 supports a follower pin 81 contacting the cam 81' fixed to the slide 55. Spring 52 keeps the cam 81' in contact with the pin 81. As the intermediate slide 75 moves back and forth, the pin 81 contacting the cam 81' causes the tool slide to move along its path of movement.

Mounted above the yoke 17 and supported thereon is the crank and control housing 20. In operation at a certain point in its travel the main housing 12 stops and the tool is rotated through an arc. To do this, I connect a crank 69 secured to the upper end of the tool support 17'. This, in turn, is connected to the piston rod 66 of a piston received within the cylinder 65, the piston being pivoted at 67 in the housing portion 20. Fluid under pressure is fed to the cylinder by means of conduits 67 and 68. The stop 70 fixed to housing 20 limits the movement of the crank and tool support. This stop extends up within the opening 69' of the crank 69. The piston rod 66 carries a block 71 which alternately contacts control switches 72 and 73. As will be explained below, these switches control the rotation of the crank as well as the movement of the housing 12.

Controls

To control movement of the housing and the rotatable tool support, various switches must be operated in a predetermined sequence for controlling the fluid under pressure to the fluid pressure operated pistons in cylinders 43' and 65. This is done by means of switches mounted adjacent the path of travel of the feed and contour cam slide and the crank operating the rotatable or pivoted tool support.

The switches controlling rotation of the crank have been described above. For controlling movement of the housing, I mount within the portion 13 of the housing three control switches 85, 86, and 87 (Figure 3) which are mounted adjacent the path of travel of the slide 51 and are operated by means of the dogs 88, 89, and 90. These dogs are secured to the slide 51. Dog 88 controls operation of the switch 85; dog 89 controls operation of switch 86; and dog 90 controls operation of the switch 87. These switches are supported in the member 13' fastened to the housing portion 13. The switches in housing 20 were described above.

Referring now to the diagram in Fig. 7, there are shown the solenoids 105, 106, 107 and 108 which controls the valves V₁ and V₂ in the conduits connected to the cylinders for permitting fluid under pressure to be directed into the cylinders 43' and 65 in the proper direction. Associated with said solenoids are the relays F and R, and F_A and R_A. Each of these relays controls the contacts bearing the same symbol as the relay. The switches 72, 73, 85, 86, and 87 are those previously identified. The starting switch 100 is connected to one side of the power line. All of the switches are shown in the position they normally assume when not in contact with either the dogs on the feed and contour slide or the block on the crank.

Referring to Figs. 3 and 7 and assuming slide 40 to be in the left-hand terminal position (Fig. 3), the dog 88 will be in contact with and have caused the switch 85 to be moved to the contact connected to R4 and away from the contact connected to F1. (As shown in Fig. 3 the slide is in its right-hand terminal position.) To start operation, the starter button switch 100 is moved to closed position. This completes a circuit through R4 and the relay F causes contact F1 to open F2, F3 and F4 to close.

Since F2 has also been closed and since the switch 87 is closed, a holding circuit is provided through the relay F keeping it closed. This is necessary since, when the

slide 40 moves to the right as will be described, switch 85 is disengaged by dog 88 and it returns to its normally closed position on the contact connected to F1 which at this time is open.

When the contact F3 closes, it completes a circuit from one side of the line through the valve solenoid 105 closed contact R_A4, closed contact F_A3 back to the other side of the line, thus energizing the valve and permitting fluid under pressure to flow into the cylinder 43' to start movement of the slide 40 toward the right.

The slide continues to move toward the right until it reaches an intermediate position. The switch 86 is contacted by the dog 89 closing the switch. Since F4 is now closed and since contact R_A2, switch 73 and contact F4 are also closed, relay F_A will be energized. Relay R_A is not energized since the contact R1 is open. When the relay F_A is energized, contacts F_A1 and F_A3 are opened and contact F_A4 is closed. When F_A3 opens, it opens the circuit through the solenoid 105 so that the slide 40 comes to rest. It is understood that during this period the tool slide has been moving radially in accordance with the contour on the contour cam 51 and the housing has been moved across the wheel being dressed in accordance with the feed cam 50.

Since F_A4 has been closed, a circuit is completed through the valve solenoid 108 which controls the fluid being directed to the cylinder 65 which controls operation of the crank 69. At this time block 71 is in contact with switch 72 and is holding it open. Then, while the housing remains stationary, the tool is pivoted through an arc. Switch 72, which was open because it was in contact with the block 71, closes when the block moves away from the switch. However, since F_A1 is open, no circuits are completed. The piston of cylinder 65 continues to function until the terminal position of the crank is reached, at which time the block 71 contacts switch 73 to open the circuit through the relay F_A which then becomes de-energized. Contacts F_A1 and F_A3 close and contact F_A4 opens. This de-energizes the solenoid 108 and stops further movement of the crank.

At this point the solenoid 105 controlling the movement of the contour and feed cam slide 40 to the right is again energized since a circuit is completed from one side of the line through F3 which is still closed, R_A4, which is closed, F_A3, which is now closed, back to the other side of the line. Switch 86 is opened when the dog 89 moves out of contact with it. Movement of the housing and tool slide are then resumed. When the slide 40 reaches its terminal position at the right of the housing (Fig. 3), dog 90 opens the switch 87 which de-energizes the relay F so that the contacts F2, F3, and F4 open de-energizing solenoid 105 and stopping further movement of the slide. However, contact F1 is reclosed; thus relay R is in position to be energized when the button 100 is closed.

To reverse the process, button 100 may again be closed. This completes a circuit through the relay R since F1, switch 85 and switch 100 are closed. R4 is opened, while R3, R2 and R1 are closed. A holding circuit for relay R is completed through switch R3. This energizes the reverse solenoid 106, since a circuit is completed through R2, 106, R_A4, F_A3 to the other side of the line. This controls the reverse valve for the piston 43' causing movement of the cam and feed slide 40 toward the left (Fig. 3). As it does so, dog 90 moves away from switch 87 permitting it to reclose, but since F2 is open, relay F is not energized. The slide continues its movement until the dog 89 re-engages the switch 86. Since switch 72 is now closed, relay R_A is energized since F_A1 and R1 are closed. Contact R_A3 is closed and contacts R_A2 and R_A4 opened. This de-energizes solenoid 106 causing movement of the slide 40 to be interrupted. However, since R_A3 is closed, a circuit is completed through the solenoid 107 energizing fluid operated piston 65 and causing rotation of the crank 69 and tool support 17'. 73

closes as block 71 moves away therefrom, but since R_A2 is open, no circuit is completed. Rotation continues until switch 72 is opened by block 71 and relay R_A de-energized. Contact R_A3 opens de-energizing solenoid 107 and stopping rotation of the crank and tool. R_A4 and R_A2 reclose. This completes a circuit through the solenoid 105 thus again initiating movement of the slide 40 to its terminal position. Switch 86 opens when dog 89 moves out of contact with it. When the slide reaches its terminal position, dog 88 opens the switch 85 de-energizing relay R, thus closing contact R4 and opening contacts R1, R2 and R3. All elements return to their normal position and further movement cannot be initiated until the switch 100 is again closed.

From the above description it will be seen that I have provided an apparatus capable of performing the functions required and one which has the advantages pointed out above.

I claim:

20 1. Apparatus for forming a contour on a grinding wheel, said contour including at least one radius of curvature, including a supporting member reciprocally movable in one direction, a tool support movably mounted on said supporting member for movement transversely of said one direction, a tool mounted on said tool support and rotatable about a vertical axis, means for moving said supporting member and said tool support, other means for rotating said tool and automatic controls for said last two means mounted on said supporting member and on said tool support for controlling movement of said supporting member and said tool supports and rotation of said tool in a predetermined sequence.

25 2. Apparatus for forming a contour on a grinding wheel, including a supporting member reciprocally movable in one direction, a tool support slidably mounted on said supporting member for movement transversely of said one direction, a tool rotatably mounted on said tool support, means including inter-connected slides and cams and a power unit for moving said supporting member and said tool support, other means including a power unit for rotating said tool controls for said last two means mounted on said supporting member and said tool support and connected to said power units for controlling movement of said supporting member and said tool support and rotation of said tool in a predetermined sequence.

30 3. Apparatus for forming a contour on a grinding wheel, including a supporting housing reciprocally movable in one direction, a tool support slidably mounted on said housing for movement transversely of said one direction, a tool rotatably mounted on said tool support, means including inter-connected slides and cams and a power unit for moving said housing and said tool support, and other means for rotating said tool and a power unit connected thereto and controls for said last two means mounted on said supporting member and said tool support and connected to said power units for controlling movement of said supporting means and said tool slide and rotation of said tool in a predetermined sequence.

35 4. A contour forming apparatus including a supporting base member, a housing movably supported on said base member for reciprocal movement in one direction, a first slide mounted on said housing and supporting a tool for movement in an arc, said first slide movable transversely of the movement of said housing, a second slide on said housing, a contour cam and a feed cam mounted on said second slide, means connected between said contour cam and said first slide for controlling movement of said tool along a path transversely of the movement of said housing, means fixed to said supporting base and contacting said feed cam for controlling movement of said housing along its path of movement, a prime mover mounted within said housing and connected to said second slide, a second housing mounted on said tool slide, means within said second housing for controlling movement of said

tool through said arc, and a first control means connected to said prime mover and other control means connected to said means for moving said tool through said arc, said first control means controlling movement of said housing in one direction and said tool in a transverse direction, and said other control means causing said housing to interrupt its movement along its path and for causing the movement of said tool through said arc during said interruption.

5. Apparatus for forming a contour on a grinding wheel, including a supporting member movable along a path, a tool support slidably mounted on said supporting member for movement transversely of said path, a tool mounted on said tool support and rotatable about a vertical axis, means including a power unit connected to said supporting member for moving said supporting member and said tool support, and other means for rotating said tool support including a power unit connected thereto, and automatic controls connected to said power units mounted on said supporting member and on said tool support for controlling movement of said supporting member and said tool support along said path, interrupting movement of said supporting member along said path causing rotation of said tool from one terminal position to another and then continuing movement of said supporting member and said tool support to a terminal position.

6. A contour forming apparatus including a tool-carrying slide, a pivoted member mounted on said slide and supporting a forming tool for movement in an arc, means connected to said pivoted member and mounted on said slide for controlling movement of the tool through said arc, a housing structure supporting said tool slide, a support slidably supporting said housing structure for movement in one direction, means for moving said housing in said one direction including a slide and a prime mover connected to said slide, means connected between said support and said slide for controlling movement of said housing, and other control means connected to said prime mover and within said housing for controlling movement of said housing and said tool slide.

7. Apparatus for forming a contour on a grinding wheel, said contour including at least one radius of curvature, a housing slidably mounted on said supporting member for movement along a path, a tool support, means on said housing rotatably supporting said tool support and movable in a direction transversely of the movement of said housing, means within said housing and connected to said supporting member for controlling movement of said housing and said tool support, and other means mounted on said tool support for controlling movement of said tool through an arc.

8. A contour forming apparatus including a supporting member, a housing slidably mounted on said supporting member for movement along a path, a tool support, means on said housing for rotatably supporting said tool support and movable in a direction transversely of the movement of said housing, means within said housing and connected to said supporting member for controlling movement of said housing and the supporting means for said tool support, and other means mounted on said tool support for controlling movement of said tool support through an arc, an electric control means mounted on said housing and on said tool support for causing movement of said housing along said path and for interrupting movement of said housing, and other electric control means connected to the means controlling movement of the tool support through an arc for causing said tool to move in an arc.

9. A contour forming apparatus including a supporting base member having a slide support thereon, a first housing slidably mounted on said slide support for movement along one path, a tool slide mounted on said housing and movable along a path transverse to the direction of movement of said housing, a rotatable tool

support on said tool slide, a contour slide mounted within said housing, a contour cam and a feed cam mounted on said contour slide, an intermediate slide connected between said contour cam and said tool slide, and a fluid pressure operated mechanism mounted on said housing for controlling movement of said housing and said tool slide and connected to said contour slide, a second housing mounted on said tool slide, fluid pressure operated mechanism connected to said rotatable tool support for rotating said tool through an arc, electric control means mounted in each of said housings and including a plurality of switch members connected to said fluid pressure operated mechanisms, said contour slide having means for operating the switch members within said first housing in a predetermined order for controlling movement of said housing along said path and for interrupting said movement, and means on the fluid pressure operated mechanism connected to said rotatable tool support for alternately contacting the switches in said second housing for controlling movement of said tool through said arc and for controlling continued movement of said housing.

10. Apparatus for forming a contour on a grinding wheel including a supporting base member having a slide support thereon, a first housing slidably mounted on said slide support for movement along a path, a tool slide mounted within said housing and movable along a path transverse to the direction of movement of said housing, a rotatable tool support mounted on said tool slide, a contour slide mounted within said housing and movable parallel to said tool slide, a contour cam and a feed cam mounted on said contour slide, an intermediate slide connected between said contour cam and said tool slide, a fixed follower mounted on said base and contacting said feed cam for controlling movement of said housing, a first prime mover mounted on said housing for controlling movement of said housing and connected to said contour slide, a second housing mounted on said tool slide, a second prime mover in said second housing connected to said rotatable tool support for rotating said tool support through an arc, control means connected to said first prime mover, control means connected to said second prime mover and means in each of said housings for operating both of said control means for controlling movement of said tool through said arc and for controlling movement of said housing.

11. Apparatus for forming a contour on a grinding wheel including a supporting base member having a slide support thereon, a movable member slidably mounted on said slide support for movement along a path, a tool slide mounted on said movable member and movable along a path transverse to the direction of movement of said movable member, a rotatable tool support mounted on said tool slide, a contour slide mounted on said movable member and movable parallel to said tool slide, a contour cam and a feed cam mounted on said contour slide, an intermediate slide connected between said contour cam and said tool slide, a fixed follower mounted on said base member and contacting said feed cam for controlling movement of said movable member, a first means mounted on said movable member for controlling movement of said movable member and connected to said contour slide, a housing mounted on said tool slide, a second means in said housing and connected to said tool support for rotating said tool support through an arc, electric control means for said first means mounted on said movable member and electric control means in said housing for said second means, and means on said movable means and said housing for operating both of said electric control means for controlling movement of said tool through said arc and for controlling movement of said movable member.

12. Apparatus for forming a contour on a grinding wheel including a supporting base member having a slide support thereon, a first housing slidably mounted

on said slide support for movement along one path, a tool slide mounted on said housing and movable along a path transverse to the direction of movement of said housing, a rotatable tool support on said tool slide, a contour slide mounted within said housing, a contour cam and a feed cam mounted on said contour slide, an intermediate slide connected between said contour cam and said tool slide, and a fluid pressure operated mechanism mounted on said housing for controlling movement of said housing and said tool slide and connected to said contour slide, a second housing mounted on said tool slide, fluid pressure operated mechanism connected to said rotatable tool support for rotating said tool through an arc, electrically controlled solenoid valves connected to said fluid pressure operated mechanism, electric control means mounted in each of said housings and including a plurality of switch members and connected to said electrically controlled solenoid valves, said contour slide having means for operating the switch members within said first housing in a predetermined order for controlling movement of said housing along said path and for interrupting said movement, and means on the fluid operated mechanism connected to said rotatable tool support for alternately contacting the switches in said second housing for controlling movement of said tool through said arc and for controlling continued movement of said housing.

13. Apparatus for forming a contour on a grinding wheel including a supporting base member having a slide support thereon, a first housing slidably mounted on said slide support for movement along a path, a tool slide mounted within said housing and movable along a path transverse to the direction of movement of said housing, a rotatable tool support mounted on said tool slide, a contour slide mounted within said housing and movable parallel to said tool slide, a contour cam and a feed cam mounted on opposite sides of said contour slide, an intermediate slide connected between said contour cam and said tool slide, a fixed follower mounted on said base and contacting said feed cam for controlling movement of said housing, and a first fluid pressure operated mechanism mounted on said housing for controlling movement of said housing and connected to said contour slide, a second housing mounted on said tool slide, a second fluid pressure operated mechanism in said second housing connected to said tool support for rotating said tool support through an arc, electrically controlled solenoid valves connected to each of said fluid pressure operated mechanisms, electric control means mounted in said first housing and connected to said electrically controlled solenoid valves, electric control means in said second housing connected to said electrically controlled solenoid valves, means on said contour slide and means on said second fluid pressure operated means for operating said electric control means for controlling movement of said tool through said arc and for controlling movement of said housing.

14. Apparatus for forming a contour on a grinding wheel including a supporting base member having a slide support thereon, a first housing slidably mounted on said slide support for movement along a path, a tool slide mounted within said housing and movable along a path transverse to the direction of movement of said housing, a rotatable tool support mounted on said tool slide, a contour slide mounted within said housing and movable parallel to said tool slide, a contour cam and a feed cam mounted on opposite sides of said contour slide, an intermediate slide connected between said contour cam and said tool slide, a fixed follower mounted on said base and contacting said feed cam for controlling movement of said housing, and a first fluid pressure operated mechanism mounted on said housing for controlling movement of said housing and connected to said contour slide, a second housing mounted on said tool slide, a second fluid pressure operated mechanism in said second housing connected to said tool support for rotating said tool support through an arc, electrically controlled solenoid valves connected to each of said fluid pressure operated mechanisms, electric control means mounted in said first housing and connected to said electrically controlled solenoid valves, electric control means in said second housing connected to said electrically controlled solenoid valves, means on said contour slide and means on said second fluid pressure operated means for operating said electric control means for controlling movement of said tool through said arc and for controlling movement of said housing, said electric control means including switches and said means on said contour slide and means on said second fluid pressure operated means including dogs and a block.
15. Apparatus for forming a contour on a grinding wheel including a supporting member, a housing slidably mounted on said supporting member for movement in one direction, a tool support, a slide rotatably supporting said tool support and mounted on said housing and movable in a direction transverse of the movement of said housing, means within said housing and means on said supporting member contacting said last means for controlling movement of said housing and the slide supporting said tool support, means for moving said housing and other means mounted on said slide for moving said tool support through an arc, control means mounted on said housing and connected to the means for moving said housing for causing movement of said housing in said one direction and for interrupting movement of said housing, and other control means on said slide and connected to the means for moving said tool support for causing said tool support to move in an arc.
